UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

WARP STOP-MOTION FOR LOOMS.

1,119,539.

Specification of Letters Patent.

Patented Dec. 1, 1914.

Application filed August 4, 1913. Serial No. 782,874.

To all whom it may concern:

Be it known that I, ALONZO E. RHOADES, of Hopedale, in the county of Worcester and State of Massachusetts, have invented 5 certain new and useful Improvements in Warp Stop-Motions for Looms, of which the following is a specification.

The reissued Letters Patent of the United States No. 11,923, July 30, 1901, to Coldwell 10 and Gildard, disclose a warp stop motion which is especially useful in weaving fabrics having a large number of warp threads. The characteristic feature of the Coldwell and Gildard warp stop motion is that the 15 detectors are arranged in two banks suspended from the lower crossing planes of the two sections into which the warp threads are divided by the lease rods, so that each detector is entirely out of contact with the 20 threads which pass through the detectors in the other bank. In this way, chafing of the threads by the detectors is prevented and warp breakage, due to the presence of the 25 detectors themselves, is substantially eliminated. This arrangement of the detectors conceals them all from view and this is 30 equally true of the detectors in their normal suspended position and also when a thread has broken and its detector has dropped. The result is that the weaver loses time in 35 locating the broken thread. Moreover, the entire weight of each detector is borne by its thread which is objectionable in the case of fine and fragile threads.

The main objects of the present invention are to render visible the detector of a broken thread, and to relieve each thread from a substantial portion of the weight of its detector, particularly in connection with the 40 Coldwell and Gildard type of warp stop motion. In addition, the present invention has a wider aspect, since a portion of the advantage is obtained even though parts 45 of the detectors are at all times exposed to view so that all of the characteristics of the Coldwell and Gildard type of warp stop motion are not present.

The present improvements are illustrated in the accompanying drawings wherein—

Figure 1 is a plan view of the improved warp stop motion. Fig. 2 is a side view. Fig. 3 is a cross section on an enlarged scale. Fig. 4 is a detail view of one of the detectors.

As shown in Fig. 3 of the drawings, the

lease rods A and B divide the warp threads into two sections, C and D, crossing each other in two different planes. Beneath the warp threads and between the lease rods are two pivot rods E and F extending transversely across the loom and beneath all of the warp threads. Upon each of these pivot rods is loosely hung a bank of thin flat sheet metal detectors, G. Each detector has an eye a, at its upper end, through which one of the warp threads pass, and a pivot aperture b, near its middle, through which one of the pivot rods E or F, loosely passes, so that the detector can freely swing upon and move along its rod. The lower end, c, of the detector is heavier than its upper end, this being partly due to the greater length and width of the lower end and partly to the presence of a lightening slot d, at the upper end which together with the eye a, reduces the weight. Accordingly, the detector is overweighed at its lower end and hence, normally, bears upwardly on its warp thread as shown in Fig. 3. Normally, both banks of detectors lie in a forwardly slightly inclined position, approaching the horizontal. The greater portion of the weight of each detector is borne by its pivot rod so that only a slight stress is brought to bear upon the thread, thereby enabling the detectors to be used with the most flimsy and delicate threads.

As shown at the right hand side of Fig. 3, the bank of detectors which normally engages the threads of section C of the warp threads is maintained clear below the other section D of the warp threads and entirely out of contact therewith, in which respect the principle of the Coldwell and Gildard patent is present. This bank of detectors is effectively prevented from coming in contact with the overlying section D of the warp threads by a transverse restraining rod H, extending across the loom between the two sections of the warp threads and between the point I of intersection between the two sections and the rear lease rod B. This rod H is close to the upper ends of the detectors of the rear bank and prevents the upward strain on the warp threads of section C (due to the overweighed lower ends of the detectors) from bringing the upper ends of this bank of detectors into contact with the overlying section D. Accordingly, this rear bank of detectors is entirely

concealed under working conditions and while the loom is running. In the event, however, of one of the warp threads of section C breaking, the overweighted lower end 5 of the corresponding detector swings the detector to an upstanding position which is shown as a vertical one in Fig. 3, thereby moving the upper end of this detector between threads of the overlying section D, 10 and thus bringing the upper end of the detector into full sight. Accordingly, when the loom stops, this upstanding exposed detector acts as a signal to direct the weaver's attention to the broken thread. Moreover, 15 the thread eye, a, of this upstanding detector is wholly above the warp threads where it is readily accessible for the reinsertion through it of the thread. While the illustrated upstanding position is shown as a 20 vertical one, it need not be so, as it suffices that a detector should swing only far enough to expose its upper end at a conspicuously different place from the normal position of the upper end.

25 The forward bank of detectors can be arranged so as to be normally concealed so that they likewise would be arranged in accordance with the principle of the Coldwell and Gildard patent. Obviously, this would be 30 the result if the illustrated front lease rod A were of sufficiently greater vertical thickness. It will be noted that no restraining rod similar to the rod H is necessary to aid in withstanding the upward strain of the front 35 bank of detectors because the front lease rod A is sufficiently close to the forward ends of the detectors when occupying their illustrated normal forwardly and upwardly inclined position. Fig. 3 of the drawings, 40 however, shows that the detectors of the front bank extend at their forward upper ends slightly above the section C of the warp threads, thus exposing their extreme upper edges so that the principle of the 45 Coldwell and Gildard warp stop motion is not exhibited. In this case, however, equally with the rear bank of detectors, the weight of the detectors on the warp threads is effectively eliminated, and when a warp 50 thread breaks, its detector assumes the vertical position and acts as a distinguishing signal to facilitate the location of the broken thread by the weaver.

In the case of both banks of detectors, the 55 movement of a detector (when its thread breaks) into an upstanding position is facilitated because the detector has to find and make its way only between one section of the warp threads.

60 When a thread breaks and its detector assumes its vertical upstanding position its lower end is between a fixed serrated back stop J and a serrated vibrating feeler K. There are two of the back stops J and two 65 of the feelers K in accordance with usual practice. A detector in its vertical position obstructs the vibration of one of the feelers and the loom is stopped through an intervening train of mechanism of well known character. As shown, the two feelers K, 70 vibrate in unison, being operatively connected together. The forward feeler is connected by a rod L with a follower M which is pivoted at e, to a longitudinally movable rod, N. This rod N is connected at its lower 75 end to a lever which in turn acts upon the shipper handle of the loom to unship it and stop the loom. The lower end of this rod N, with its connections, are not shown, because constituting no part of the invention. 80 They are shown in the United States Letters Patent to Clement, No. 645,912, March 20, 1900. The follower M is moved in one direction by a cam O on the cam or low shaft P of the loom and in the opposite direction by 85 a spring which is not shown but which is similar to the spring shown in the United States Letters Patent to Draper, No. 797,671, August 22, 1905. When the warp stop detectors are elevated, the follower M oscillates 90 on its pivot e, thus vibrating the two feelers K, K. When, however, a warp thread breaks and an upstanding detector obstructs the vibration of one of the feelers, the follower M, is not swung on its pivot e, by the cam O, but the cam acting upon the follower lifts the rod N and thus stops the loom in the manner set forth in the aforesaid Clement Patent No. 645,912.

The several rods E, F, and H, are held at 95 their ends in slotted bearings f, by removable cotter pins g, and the lease rods A and B are held at their ends in their supports by removable cotter pins g, thus enabling the ready removal of the detectors and lease rods for drawing in and facilitating their replacement when a new warp is to be put in the loom.

The detectors, their pivot rods, the lease rods, the back stops J, and the feelers K are 100 all mounted upon the frame Q which is adjustably fastened to the side frames R of the loom by means of slots S and bolts T. These connections are shown for one side of the loom only. The same connections are 105 used at both sides of the loom.

I claim:—

1. A loom having, in combination, lease rods dividing the warp into two intersecting sections; two transverse pivot rods located 110 below the warp and between the lease rods; two banks of detectors, one for each pivot rod, each detector being loosely hung on one of the pivot rods, being overweighted at its lower end and having a warp thread eye at its upper end, and each detector when threaded occupying a position slightly inclined from the horizontal and extending upwardly and forwardly from its rear end, and the two sections of warp threads pass- 115

ing through the eyes of the respective banks of detectors on opposite sides of and below their crossing; a restraining rod between the sections of warp threads and between the warp-thread intersection and the rear lease rod and near the front ends of the rear bank of detectors; a back-stop for each bank of detectors; and a vibrating feeler which encounters a detector when, on the breakage of its warp thread, it occupies its upstanding position with its lower end between its back stop and feeler.

2. A loom having, in combination, lease rods dividing the warp into two intersecting sections; two transverse pivot rods located below the warp and between the lease rods; two banks of detectors, one for each pivot rod, each detector being loosely hung on one of the pivot rods, being overweighted at its lower end and having a warp thread eye at its upper end, and each detector when threaded occupying a position slightly inclined from the horizontal and extending upwardly and forwardly from its rear end, and the two sections of warp threads passing through the eyes of the respective banks of detectors on opposite sides of and below their crossing; a restraining rod between the warp-thread intersection and the rear lease rod and near the front ends of the rear bank of detectors; a back-stop for each bank of detectors; and means coöperating with the lower end of an upstanding detector to stop the loom.

3. A loom having, in combination, lease rods dividing the warp into two intersecting sections; two transverse pivot rods located below the warp and between the lease rods; two banks of detectors, one for each pivot rod, each detector being loosely hung on one of the pivot rods, being overweighted at its lower end and having a warp thread eye at its upper end, and each detector, when threaded, occupying a position slightly inclined from the horizontal and the two sections of warp threads passing through the eyes of the respective banks of detectors on opposite sides of and below their crossing; and a restraining rod between the sections of warp threads and near the ends of the bank of detectors which engages the section of warp threads that passed beneath the restraining rod.

4. A loom having, in combination, lease rods dividing the warp into two intersecting sections; two transverse pivot rods located below the warp and between the lease rods; two banks of detectors, one for each pivot rod, each detector being loosely hung on one of the pivot rods, being overweighted at its lower end and having a warp thread eye at its upper end, and each detector, when threaded, occupying a position slightly inclined from the horizontal and extending

upwardly and forwardly from its rear end, and the two sections of warp threads passing through the eyes of the respective banks of detectors on opposite sides of and below their crossing and means coöperating with an upstanding detector to stop the loom.

5. A loom having, in combination, lease rods dividing the warp into two intersecting sections; two banks of detectors, one for each section, each detector being pivoted at its middle below both warp sections, being overweighted at its lower end and having a warp thread eye at its upper end, and, when threaded, occupying a position slightly inclined from the horizontal and extending upwardly and forwardly from its rear end, and the two sections of warp threads passing through the eyes of the respective banks of detectors on opposite sides of and below their crossing; and means coöperating with an upstanding detector to stop the loom.

6. A loom having, in combination, lease rods dividing the warp into two intersecting sections; two banks of detectors, each detector being pivoted at its middle below both warp sections, being overweighted at its lower end and having a warp thread eye at its upper end, and, when threaded, occupying a position slightly inclined from the horizontal, and the two sections of warp threads passing through the eyes of the respective banks of detectors on opposite sides of and below their crossing; and means coöperating with the overweighted end of an upstanding detector to stop the loom.

7. A loom having, in combination, means for dividing the warp into two sections in different planes; a transverse pivot rod below both sections; a bank of detectors loosely hung on said pivot rod, each detector being overweighted at its lower end and having an eye at its upper end through which passes one of the threads of the lower warp section, the relation of the warp separation and the detectors being such that, when the threads are normal, the detectors are wholly below the upper warp sections, but, when a thread breaks and its detector assumes an upstanding position, the eye of such detector is above the upper warp section and is exposed to view; a restraining rod between the two warp sections and near the eye ends of the detectors when in their normal position which restrains the lower warp sections from upward movement against the upward stress of the detectors; and means coöperating with the lower end of an upstanding detector to stop the loom.

8. A loom having, in combination, means for dividing the warp into two sections in different planes; a transverse pivot rod below both sections; a bank of detectors loosely hung on said pivot rod, each detector being overweighted at its lower end and having an eye at its upper end through which passes

one of the threads of the lower warp section, the relation of the warp separation and the detectors being such that, when the threads are normal, the detectors are wholly below 5 the upper warp sections, but, when a thread breaks and its detector assumes an upstanding position, the eye of such detector is above the upper warp section and is exposed to view; and means coöperating with the 10 lower end of an upstanding detector to stop the loom.

9. A loom having, in combination, means for dividing the warp into two sections in different planes; detectors pivoted at their 15 middles below both warp sections, each detector being overweighted at its lower end and having an eye at its upper end through which passes one of the threads of the lower warp section, the relation of the warp separation and the detectors being such that, when the threads are normal, the detectors are wholly below the upper warp sections, but, when a thread breaks and its detector assumes an upstanding position, the eye of 20 such detector is above the upper warp section and is exposed to view; and means coöperating with the lower end of an upstanding detector to stop the loom.

10. A loom having, in combination, means 30 for dividing the warp into two sections in

different planes; detectors pivoted at their middles below both warp sections, each detector being overweighted at its lower end and having an eye at its upper end through which passes one of the threads of the lower 35 warp section, the relation of the warp separation and the detectors being such that, when the threads are normal, the detectors are wholly below the upper warp sections, but, when a thread breaks and its detector 40 assumes an upstanding position, the upper end of such detector is above the upper warp section and is exposed to view; and means coöperating with the lower end of an upstanding detector to stop the loom. 45

11. A thin sheet metal warp stop detector having a pivotal aperture at its middle, a thread eye near its upper end and a lightening slot between the pivotal hole and the eye, and the lower end below the pivotal 50 aperture being longer and wider than the upper end above said aperture.

In witness whereof, I have hereunto signed my name in the presence of two subscribing witnesses.

ALONZO E. RHOADES.
